CONTROL MECHANISM

Walter O. Lum, Schenectady, N. Y., assignor to
 General Electric Company, a corporation of
 New York

Application March 31, 1934, Serial No. 718,395

8 Claims. (Cl. 158—42.1)

My present invention relates to control mechanisms, particularly safety circuit control switches and to furnace control systems embodying safety circuit control switches. One of the objects is 5 to provide an improved mechanism for transmitting motion whereby a safety control switch may be operated from one control position to another in response either to a single reciprocation of a given amplitude of a reciprocating motion transmitting element or to a series of reciprocations of lesser amplitude of the element. Another object is to embody such a safety control switch mechanism in a furnace control system.

10 In order that the principles underlying my invention may be clearly understood I have described and illustrated different embodiments thereof in a control switch mechanism and also described and illustrated the manner in which such switch mechanism may be embodied in a furnace control system.

In the operation of oil burner equipment there is danger of conditions arising such that abnormal pressures, sometimes of an explosive nature, 15 will develop in the combustion chamber. It has been the practice to provide safety doors or like vent means to relieve these abnormal pressures. Since such abnormal pressures are due to improper functioning of the burner mechanism, it 20 is desirable to deenergize the fuel supplying apparatus and control therefor immediately upon the occurrence of the abnormal pressure, and mechanism for effecting such deenergization of the oil burner equipment in response to abnormal 25 pressures forms the subject matter of my co-pending application, Serial No. 596,067, filed March 1, 1932 and assigned to the assignee of the present invention. In the apparatus therein described, a safety switch, connected to an explosion relief door by means of a chain or like 30 connection, is automatically operated to stop operation of the fuel supplying apparatus and control therefor in response to actuation of the relief door by puffback or other abnormal pressure.

40 There also may occur in the operation of oil burner equipment, improper operating conditions which will not be of such nature as to cause abnormal pressure of explosive proportions but 45 which will cause irregularly recurring pulsations of abnormal pressure of relatively small magnitude. It has been found in the operation of an oil burner apparatus equipped with safety mechanism such as described in my above referred to 50 application, that such small pulsations of ab-

normal pressure will cause the pressure release door to vibrate to an extent sufficient only to allow the escape of puffs of undesirable fumes without being sufficient to completely operate the safety switch to open-circuit position. In other 5 words, the amplitudes of the successive outward movements of the door, which is biased to return to closed position, will not be sufficient to move the elements of the safety switch a sufficient distance with respect to each other to disengage 10 them. It is desirable, however, to deenergize the oil burner equipment upon the occurrence of such relatively small pulsating abnormal pressures as well as upon the occurrence of abnormal 15 pressures of explosive proportions, since both 20 denote improper operation of the burner equipment. A further and more specific object of my invention is, therefore, the provision of improved, simple and reliable control mechanism for insuring deenergization of an oil burner 25 equipment upon either a single opening of the oil burner pressure relief door to a predetermined degree or a series of openings of the door to lesser degrees.

Fig. 1 is a schematic showing of an oil burner 25 furnace, partially cut away, to which my invention is applied; Fig. 2 is a detailed perspective showing of the elements of one embodiment of my invention; and Figs. 3, 4, and 5 illustrate successive steps in the operation of the mechanism shown in Fig. 2. Figs. 6, 7, and 8 illustrate another embodiment of my invention and successive steps in the operation thereof, and Fig. 9 illustrates schematically the manner of applying this last embodiment to an oil burner furnace 30 35 similar to that shown in Fig. 1.

Referring to the drawing, an oil burner furnace 10 having a combustion chamber 11, is equipped with a motor operated pump and compressor unit 12 for supplying fuel and air to an atomizing nozzle 13. The combustion mixture discharged from the nozzle into the combustion chamber is ignited by means of electrodes 14 and the products of combustion pass from thence through the stack breeching 15 into the smoke 40 pipe 16 which leads to the stack. A pressure relief port 17 is incorporated in the top of the stack breeching, and a pressure relief door 20, pivotally mounted on the breeching as shown at 45 50 55 21, is biased by means of spring 22 to close the relief port.

Electrical energy for the operation of the burner mechanism and the electrodes is supplied from lines 23, 24 through a safety switch which is shown at 25 as consisting of a terminal box 55

28 secured to the stack bracketing by means of mounting plate 27 and provided with a socket 28 to which the electrical leads from lines 23, 24 are brought by means of conduit 29. A movable 5 switch element in the form of a plug 30 having contacts 31, 32, is provided for bringing the terminals in the socket 28.

In accordance with my present invention, a one-way force transmitting mechanism is provided for connecting the door 20 with the contact carrying plug 30 and for effecting disengaging movement of the plug either in a single step in response to opening of the door to a predetermined distance or in a series of steps in response 10 to a series of openings of the door to lesser distances. The principal element of this mechanism is a link member, in the form of a hook-shaped segment 35, pivotally mounted at 33 upon clamp 34 secured to the free end of the door 20. The 15 segment engages a slotted stirrup 36 attached to the plug 30 and is arranged to depend from the pivotal mounting with its free end extending through the slot and its inner face 37 in frictional engagement with the underneath side of the 20 closed end of the slot in the stirrup. This inner face 37 of the segment is in the form of an irreversible cam surface, successive points of which as illustrated by points *a* and *b*, are at progressively shorter distances from the pivot point 33, 25 and therefore from the free end of the door 20. It is preferred that the cam surface be continuous for reasons hereinafter to be set forth. A weight 38 is affixed to the hook-shaped segment at some point horizontally offset from the vertical line of 30 motion of the pivot point 33 so that it will provide a relatively large gravitational force acting about the lever arm, consisting of the portion of the segment between the weight and the pivot point, to tend to swing the segment in a counterclockwise 35 direction as viewed in Figs. 2 to 5 inclusive.

In the operation of the oil burner equipment conditions may arise in the combustion chamber which will produce abnormal pressures of sufficient magnitude to blow open the door 20. When 40 the door is blown open by a puffback, explosion or similar large abnormal pressure the movement thereof will be sufficient to disengage the contacts 31 and 32 of the plug 30 from the terminals in the socket 28 in a single stroke to deenergize 45 the oil burner and ignition equipment. It will be apparent that upon upward movement of the door 20 the frictional engagement of the inner surface of the hook-shaped segment 35 with the end of the stirrup 36 will become a positive engagement 50 to provide a positive operating connection between the door and the movable plug so that outward movement of the door will pull the plug upward a distance proportional to the amplitude 55 of the movement of the door, and a single opening of the door to a predetermined degree will be sufficient to completely disengage the contacts of the safety switch 25.

There might also arise in the operation of the oil burner conditions such that pulsating pressures of small magnitude may occur within the combustion chamber, and these pulsations will be sufficient to impart to the pressure relief door only a vibratory opening movement such that each 60 upward movement of the door will be of insufficient amplitude to completely disengage the contacts of the safety switch 25. Such conditions are, of course, undesirable since they denote improper operation of the oil burner equipment and will also allow continued escape of combustion 65 gases from the pressure relief port into the space 70

surrounding the oil burner furnace. Hence it is desirable to have the oil burner equipment de-energized after repetition of this pulsating condition for a certain length of time. Figs. 3, 4, and 5 illustrate in two steps the operation of the safety switch in response to vibration of the pressure release door 20, but it is to be understood that this is merely illustrative and that it may take a much larger number of successive steps to completely disengage the contacts of the safety 10 switch. When the door 20 is at rest in closed position and the plug 30 is completely seated in the socket 28 which is the normal condition for proper operation of the furnace, a point on the cam surface 37 having a connection distance denoted *a* will engage the stirrup 36. Upon a slight upward movement of the door 20 due to a pulsation of abnormal pressure the plug 30 will be caused to follow the movement of the door 20 in proportion to the extent of opening thereof. This 15 will effect a partial disengagement of the plug contacts from the terminals of the box 26 as shown in Fig. 4. Now upon return of the door to its closed position, were it not for the weight 38 the segment would tend to retain its original 20 position as shown in the dotted lines of Fig. 4, and would tend to push the plug back into the socket in the terminal box 26. However, the biasing effect of the weight 38 tends to cause the segment to rotate in a counterclockwise direction, 25 thus forcing a succeeding bearing point of the cam surface into engagement with the stirrup 36, such successive bearing point having a connection distance such as *b* which is shorter than that of the connection distance *a* of the bearing 30 point which first engaged the stirrup 36. This 35 will produce a shorter connection distance between the door and the plug 30 so that succeeding upward movements of the door will produce added increments of upward movement of the 40 plug and will eventually effect complete disengagement of the contacts 31 and 32 from the terminals of the terminal box 26 as illustrated in Fig. 5. It will thus be seen that my improved 45 linkage mechanism provides means for imparting progressive increments of movement to the movable switch element or plug 30 upon successive vibration of the pressure relief door 20, and that a predetermined summation of the outward 50 movements of the door will effect complete disengagement of the safety switch to deenergize the electrical circuit of the oil burner and ignition equipment. It is also apparent that the continuity of the cam surface provides for infinitely small 55 changes in connection length so that the mechanism will function regardless of the amplitude of movement of the door.

Figs. 6 to 9 inclusive illustrate a modified form of my invention wherein the linkage mechanism is particularly adapted for use with a pressure relief door having substantially horizontal movement. The operating link in this embodiment is in the form of a closed segment 40 having an inner bearing face 41 similar to the irreversible cam surface 37 of the link 35 in the embodiment first 60 described. A weight 42 of arcuate shape similar to that of a portion of the segment is riveted or otherwise fastened to the segment as shown at 43 and 44.

Terminal box 26 is incorporated in the wall of 70 the furnace 10, and the socket therein is flush with the wall. Plug 30 is provided with one or more projecting ears 45 for engagement with the inner surface of the segment. The segment is pivotally secured by means of pin 46 upon the 75

end of rod 47 which passes through an opening 48 in the adjacent side of the stack breeching and through the interior thereof to the opposite side where it is fastened to the pressure relief door 50 which is arranged to close the port 51 in the wall of the breeching. Guide means 52 are provided to steady the rod and aid in holding it and the door in position, and spring means 53 are provided to bias the door in closed position.

The operation of the mechanism of the embodiment last described is similar to that described in connection with Figs. 2 to 5 inclusive. Under normal conditions in the furnace, the projection 45 will be engaged by a bearing point on the cam surface which has a connection distance *a*. Outward movement of the door 50 will cause the rod 47 to slide in the guides 48 and 52. This will cause segment 40 to pull on the plug 30 and effect partial disengagement of the contacts 31 and 32 to an extent proportional to the distance of opening of the door, as for instance, to a position such as shown in Fig. 7. Subsequent return of the door to closed position releases the frictional force between the bearing surface 41 of the segment and the projection 45, and allows the segment to swing in a counter-clockwise direction under the influence of weight 42 until a succeeding bearing point having a shorter distance, such as *b*, is forced into engagement with the projection. Thus, successive outward vibrations of the door impart progressive increments of movement to the movable switch member or plug and will completely disengage the contacts of the plug from the terminals in the terminal box, as shown in Fig. 8, after a predetermined summation of said increments of movement. When the plug is completely disengaged it will hang suspended from the segment by means of the projecting ear 45 which will rest upon the lower portion of the segment 40, and the plug must be manually reset to reestablish the energizing circuit of the oil burner. It will be evident that the link may be made in the form of two segments, having similar contours, fixedly secured to each other in spaced apart side by side relation and pivotally mounted on opposite ends of the pivot pin 46, and the bearing surfaces of these two segments may be arranged to engage projecting ears 45 on opposite sides of the plug 30.

From the foregoing description it will be seen that by my invention I have provided a mechanism for greatly increasing the safety and reliability of operation of an oil burner furnace. The embodiments of the invention herein illustrated and described have been selected for the purpose of setting forth the principles involved. It will be apparent, however, that the invention is susceptible of being modified to meet different conditions of use and that its use is not limited to a switching mechanism for an oil furnace safety switch but may be employed with equal advantage in any situation where a control mechanism having similar characteristics is desired. Such modifications are believed to be within the spirit and scope of my invention and are intended to be covered by the appended claims.

What I claim as new and desire to secure by Letters Patent of the United States, is:—

1. The combination with a furnace having a combustion chamber, electrically operated fuel burner means therefor and an energizing circuit for said electrically operated means, of electrical switch means movable between two circuit controlling positions to control the energization of said circuit, a pressure relief door normally biased

to closed position and arranged to open different distances in response to abnormal pressures of different magnitudes within the combustion chamber, and means for effecting either continuous movement of the switch means from one of said circuit controlling positions to the other in response to a single opening of the door to a predetermined distance or step by step movement of the switch means from one circuit controlling position to the other in response to a series of lesser openings of the door.

2. The combination with a furnace having a combustion chamber, electrically operated fuel burner means therefor and an energizing circuit for said electrically operated means, of electrical switch means movable between two circuit controlling positions to control the energization of said circuit, a pressure relief door normally biased to closed position and arranged to have different degrees of opening in response to abnormal pressures of different magnitudes within the combustion chamber, and means interconnecting the door and the switch means including a one-way force transmitting mechanism for effecting movement of the switch means from one of said circuit controlling positions to the other in response either to a single opening of the door to a predetermined degree or to a predetermined summation of openings of the door to lesser degrees.

3. The combination with a furnace having a combustion chamber, electrically operated fuel burner means therefor and an energizing circuit for said electrically operated means, of switch means movable between two circuit controlling positions to control the energization of said circuit, movable pressure responsive means operatively associated with the furnace to vibrate in response to pulsating abnormal pressures within the furnace combustion chamber, and means interconnecting the pressure responsive means and the switch means for effecting progressive movement of the switch means from one of said circuit controlling positions to the other in response to repeated vibration of the pressure responsive means due to repeated pulsations of abnormal pressure in the combustion chamber.

4. The combination with a furnace having a combustion chamber, electrically operated fuel burner means therefor and an energizing circuit for said electrically operated means, of switch means operable to control the energization of said circuit and means for insuring deenergization of said circuit upon the occurrence of pulsating abnormal pressures in the combustion chamber including a pressure relief door operatively associated with the furnace and vibratory movable in response to said pulsating abnormal pressures, biasing means for holding the door normally in closed position, and means interconnecting the door and the switch means including a one-way force transmitting mechanism for imparting progressive increments of movement to said switch means toward open circuit position in response to a series of successive vibrations of the door due to said pulsating abnormal pressures.

5. In combination, electric circuit controlling means having a switch element movable between two circuit controlling positions, and means for transmitting motion to said element including a movable element and a one-way force transmitting mechanism interconnecting said switch element and movable element for effecting movement of the switch element from one to the other of said circuit controlling positions in re-

sponse to either a single movement of said movable element through a predetermined distance or the repeated movement of the movable element through a lesser distance.

- 5 6. In combination, circuit controlling means having a switch element movable between two circuit controlling positions, and means for transmitting motion to said element including a reciprocating element, and a one-way force transmitting mechanism mechanically interconnecting said switch element and said reciprocating element for moving said switch element from one to the other of said circuit controlling positions in response to either a single reciprocation of the reciprocating element through a predetermined distance or a series of reciprocations of said reciprocating element through a lesser distance.
- 10 7. In combination, circuit controlling means having a switch element movable between two circuit controlling positions, and mechanism for transmitting motion to said element including a 10
- 15 15 pair of relatively movable members, one being pivotally mounted and having a one way interlocking engagement with the other member and biased to successively shorten the distance between the mounting point of said one member and the other member upon reciprocation of one of said members to effect progressive increments of movement of the switch element between said positions.
- 20

pair of members having a one way interlocking engagement for movement thereof as a unit with said switch and biased to have relative movement therebetween in the opposite way to provide a movable connection of varying lengths with the 5 switch element.

8. In combination, circuit controlling means having a switch element movable between two circuit controlling positions, and mechanism for transmitting motion to said element including a 10 pair of relatively movable members, one being pivotally mounted and having a one way interlocking engagement with the other member and biased to successively shorten the distance between the mounting point of said one member and 15 the other member upon reciprocation of one of said members to effect progressive increments of movement of the switch element between said positions.
